UNITED STATES PATENT OFFICE

141,769

DESIGN FOR A GOLF CLUB HEAD

Howard P. G. Newsome, New Orleans, La.

Application April 9, 1945, Serial No. 118,929

Term of patent 14 years

(Cl. D34—5)

To all whom it may concern:

Be it known that I, Howard P. G. Newsome, a citizen of the United States, residing at New Orleans, in the parish of Orleans and State of Louisiana, have invented a new, original, and ornamental Design for Golf Club Heads, of which the following is a specification, reference being had to the accompanying drawing, forming a part thereof, in which

Fig. 1 is a rear elevation of a golf club head, showing my new design,

Fig. 2, a section on line 2—2 of Fig. 1,

Fig. 3, a section on line 3—3 of Fig. 1, and

Fig. 4, a section on line 4—4 of Fig. 1.

The essential and characterizing feature of my design is the surface configuration of the rear non-striking face of the club head, with a wide groove extending from end to end thereof and with a gradual increase in thickness of metal between the striking face and the bottom of said groove toward the toe end of the club, substantially as shown in the drawing.

I claim:

The ornamental design for a golf club head, as shown and described.

HOWARD P. G. NEWSOME.
